I.L.Landis,

Portable Fence,

No 65,819-

Patented June 18, 1867

Inventor:

Israel Landis.

United States Patent Office.

ISRAEL L. LANDIS, OF LANCASTER, PENNSYLVANIA.

Letters Patent No. 65,819, dated June 18, 1867.

IMPROVEMENT IN FENCE.

The Schedule referred to in these Letters Patent and making part of the same.

TO ALL WHOM IT MAY CONCERN:

Be it known that I, ISRAEL L. LANDIS, of Lancaster, in the county of Lancaster, and State of Pennsylvania, have invented a new and simplified Mode of Securing Portable Fences; and I do hereby declare that the following is a full and exact description thereof, reference being had to the accompanying drawings, making a part of this specification, in which—

Figure 1 shows two panels of my fence set up.

Figure 2, the base-timber and wire braces.

Figure 3, a panel of pale-fence for the same base and braces, when set up.

Figure 4, illustrations of uneven ground and the adaptation of the fencing or base-timbers to the slope.

The nature of my invention is in avoiding all framing, and to make a light panel, adapted to rolling soil, and which a single individual can put up with ease and make a permanent fence that will prove satisfactory.

To enable any farmer to make and use my invention, it is only necessary to say that the posts P being, say, double the thickness and width of the rails R, 1, 2, 3, 4, and 5. The rails of the ordinary length are firmly nailed to the posts, parallel to each other, in the usual manner, only, that the top rails 1 or 2 project beyond the post say six or eight inches, while the other rails project only half that distance, three or four inches. The bed-timber B may be a piece of common cord-wood four feet long, or a sill cut out of squared timber, with a central notch or groove for the reception of a portion of the projection of the lower rail or post. These sills have a large headed spike, or its equivalent, driven in on each end, as shown. Being provided with the panels (fig. 1 or fig. 3) and the sills B, and a coil of sufficiently stout annealed wire, all is ready for setting up. The sill being laid across the line of fencing at right angles thereto, the top projections, 1 or 2, of two adjoining panels are lapped one behind the other, the lower projections 5 set in the notch, a temporary prop for the first panel, will enable the farmer personally to set it up with ease, the wire w being wrapped around one spike, s, and once or twice around the two over-lapping top rails, holding the posts perpendicular, or nearly so. The other end of the wire is carried down and wrapped around the spike s on the opposite side. This secures the top and bottom rails, and at the same time braces them.

It is evident that the wire braces are readily adjusted while putting on, to set the posts with their panels vertically, and adapt the sills to the slope of the ground, as well as the panels also. The adjustability of the wire, the single sill, with its notch and spikes, so simplifies matters as to make this a truly portable fence, applicable to all purposes for which such fences may be required, and decidedly the cheapest fence, there being no waste of materials. I am aware that the base-timber is used with framed pieces in place of the wire, and that panels with projecting rails are not new. But I am not aware that any arranged in the specific manner shown, and secured by wire braces for connecting the upper united rails with the sills, have ever been used.

What I claim as my improvement, and desire to secure by Letters Patent, is—

So constructing the panels of a fence that one of the rails of each panel shall overlap the corresponding rail of the adjoining panel, and securing the same together by a wire brace in the manner specified.

I also claim specially the mode of fastening shown in Figure 5.

ISRAEL L. LANDIS.
